UNITED STATES PATENT OFFICE.

KARL H. HANSEN, OF PITTSBURGH, PENNSYLVANIA, ASSIGNOR TO ORENSTEIN-
ARTHUR KOPPEL CO., OF PITTSBURGH, PENNSYLVANIA.

DUMP-CAR.

1,106,805.

Specification of Letters Patent. Patented Aug. 11, 1914.

Application filed June 8, 1912. Serial No. 702,588.

To all whom it may concern:

Be it known that I, KARL H. HANSEN, a citizen of the United States, and resident of Pittsburgh, in the county of Allegheny and 5 State of Pennsylvania, have invented a new and useful Improvement in Dump-Cars; and I do hereby declare the following to be a full, clear, and exact description thereof.

My invention relates to dump-cars of the 10 tilting-body type.

The object of my invention is to provide a simple and efficient form of mechanism for 15 tilting the body of the car by a direct positive vertical push from a vertically actuated piston located on the underframe.

Referring to the accompanying drawings Figure 1 is a longitudinal elevation of a car embodying my invention; Fig. 2 is a cross section on line 2--2 Fig. 1, one of the arms 20 being removed to make the illustration clear; Fig. 3 is a similar view showing the car in dumping position; and Fig. 4 is a view looking in the direction of the arrow 4 Fig. 3, the car body being broken away, and the 25 lugs on the car body shown in section, and Fig. 5 is an enlarged perspective view of the push member.

In Fig. 1 I have illustrated a dump-car of the tilting-body type, in which the car is 30 pivotally mounted along a center line, and as my invention does not relate to the details of the construction of the underframe and other parts it will not be necessary to refer to same in detail. The dumping-body 2 is provided with the brackets 3 which are pivotally mounted on the standards 4 of the underframe by means of the pivotal pins 5. At or about the mid-point of the car are the 35 cylinders 6 and 7 which are supported in any suitable manner on the underframe. Air or other motive fluid may be supplied to said cylinders from any suitable source. The piston-rods 8 are connected to suitable pistons within the cylinders and the upper ends 40 of said piston rods carry the cross-heads 9. These cross heads have the trunnions 10 projecting out therefrom. Brackets 11 are secured to the bottom of the car at each side of the center line of said car and said brackets 45 are provided with the lugs 12. A clevis-member 13 is connected to the bracket 10 by means of a pin 14 and in this manner said clevis-member is adapted to swing on said bracket. The clevis member 13 is provided 50 with the ears 15 to which the arms 16 are

pivoted by pins 17. The mounting of these arms in this manner holds the pin 14 in position and prevents its dislodgment as clearly indicated in Fig. 4. The arms 16 in the normal position of the car hang in a substantially vertical position, and when in this position the faces 18 abut. The lower ends of the arms 16 are provided with the seats 19 with the curved upper portion 20 to receive the trunnions of the cross-heads 9. The arms are further recessed as at 21 to receive the cross-head 9 when the cross-head is moved up to engage said arms. The clevis-member 13 and the arms 16 form what may be broadly termed "a push-member".

The lower ends of the arms 16 are beveled as at 22 and below said arms and in the path of same, on the descent of said arms, are the inclined planes 23 located adjacent to the cylinder heads. These inclined planes act 75 to deflect or force the arms 16 apart, as clearly indicated in Fig. 4, when the car is dumped in the position indicated in Fig. 3, as more fully hereinafter set forth.

The clevis-member 13 is provided with the 80 stop 24 and said stop acts to regulate the movement of the push-member when the car is dumped, as indicated in Fig. 3. In this position of dumping the stop 24 comes in contact with the bottom of the car or other 85 fixed abutment, and prevents the push-member swinging into a vertical position which it would naturally assume, the purpose of this being to hold the push-member in a position approximately at right angles to 90 the bottom of the car when the piston 8 is elevated, so that there will be a direct vertical thrust of the piston, and the push-member will be held from swinging over and causing a side thrust on the piston-rod 8. 95

In the dumping operation one of the chains 25 having been released, motive fluid is admitted to the cylinder 7 at one side of the car and the piston-rod 8, together with the cross-head 9, are moved upward. The 100 cross-head moves into engagement with the recesses 21 in the lower ends of the arms 16 and the trunnions 10 fit in the bearings 20. As the upward push of the piston is in a vertical line there is no tendency of the arms 105 16 to separate, and as the stop 24 on the clevis member engages the bottom of the car the arms 16 are held from swinging into a vertical position, and consequently the direct vertical push of the piston rod dumps 110

the car. After the car has moved sufficiently the push-member will separate from the cross head as indicated in Fig. 3. This will not occur, however, until after the piston 5 has done its work. The stop 24 prevents the swinging of the push-member and consequently obviates the side thrust on the piston rod during the upward movement of same. As the opposite side of the car is 10 lowered the arms 16 on that side come in contact with the inclined planes 23 and said arms are deflected or separated, the bevel portions 22 traveling down the inclines 23 and gradually spreading said arms until 15 they assume the position indicated in Fig. 4. In this manner therefore provision is made for moving said arms out of the way so as not to interfere with the cylinder-head 6. When the car-body is brought back to 20 normal position after the dumping operation, the arms 16 will resume their normal positions at opposite sides of the car and said car is then in position to be dumped from either side as may be desired.

25 By my invention I provide means for dumping the car-body by the use of a fluid operated piston with a piston-rod moving in a vertical line and applying a direct vertical push to the push member while at the 30 same time the push arms at the opposite side are deflected so that there is no interference with the downward movement of the car-body on that side.

What I claim is:

35 1. In a dump-car, the combination of a tilting car-body, a vertically actuated piston-rod, a pivotally mounted push-member in the path of said piston-rod, and means for maintaining said push-member at substantially right angles to the bottom of said car 40 in the tilting position of the car-body.

2. In a dump-car, the combination of a tilting car-body, a vertically actuated piston-rod, a pivotally mounted push-member carried by said car-body in the path of said piston-rod, and a stop carried by said push-member adapted to engage said car-body when said piston rod is elevated.

45 3. In a dump-car, the combination of a 50 tilting car-body, a vertically actuated piston-

rod, a push-member carried by said car-body comprising swinging arms in the path of said piston-rod, and means for deflecting said arms on the side the car is dumped.

4. In a dump-car, the combination of a 55 tilting car-body, a vertically actuated piston-rod, a push-member carried by said car-body comprising a pair of swinging arms in the path of said piston-rod, and means in the path of said arms to deflect same.

60 5. In a dump-car, the combination of a tilting car-body, a vertically actuated piston-rod, a push-member carried by said car-body comprising a pair of swinging arms, and inclined planes in the path of movement 65 of said arms to deflect same.

6. In a dump-car, the combination of a tilting car-body, a vertically actuated piston-rod, a push member carried by said car-body comprising swinging arms, said arms 70 having beveled portions at the lower ends, and inclined planes in the path of said arms to deflect same.

7. In a dump-car, the combination of a 75 tilting car-body, a vertically actuated piston-rod, a push-member carried by the car body comprising swinging arms, and a cross-head on said piston-rod adapted to engage said arms.

8. In a dump-car, the combination of a 80 tilting car-body, a vertically actuated piston-rod, a push-member comprising a pair of swinging arms having recesses at the lower ends thereof, and a cross-head on said piston-rod adapted to engage said recesses.

85 9. In a dump-car, the combination of a tilting car-body, a vertically actuated piston-rod, a cross-head on said piston-rod, trunnions on said cross-head, a push-member comprising a pair of swinging arms having 90 recesses at the lower end to receive said cross-head, and seats to receive said trunnions.

In testimony whereof, I the said KARL H. HANSEN have hereunto set my hand.

KARL H. HANSEN.
